US00D814900S

(12) **United States Design Patent** (10) Patent No.: **US D814,900 S**
(45) Date of Patent: **** Apr. 10, 2018**

(54)	BLADE FOR OSCILLATING POWER TOOLS	4,015,371 A	4/1977	Grayston
(71)	Applicant: BLACK & DECKER INC. , New Britain, CT (US)	4,059,930 A	11/1977	Alessio
		4,106,181 A	8/1978	Mattchen
		4,112,541 A	9/1978	Tetradis
		4,252,121 A	2/1981	Arnegger
		4,253,776 A	3/1981	Orain
(72)	Inventors: Thomas R. Kaye, Jr. , Fallston, MD (US); Bradley J. Nohr , Bel Air, MD (US)	4,265,285 A	5/1981	Fodor
		4,386,609 A	6/1983	Mongeon
		4,393,626 A	7/1983	Schroer
		4,513,742 A	4/1985	Arnegger
		4,590,837 A	5/1986	Nanba
(73)	Assignee: Black & Decker Inc. , New Britain, CT (US)	4,597,227 A	7/1986	Gentischer et al.
		4,599,077 A	7/1986	Vuillard
		4,648,735 A	3/1987	Oddenino

CLAIM

The ornamental design for a blade for oscillating power tools, as shown and described.

DESCRIPTION

FIG. 1 is a top perspective view of a blade for oscillating power tools showing our new design in accordance to a first embodiment;

FIG. 2 is a right side elevation view thereof;
FIG. 3 is a left side elevation view thereof;
FIG. 4 is a rear elevation view thereof;
FIG. 5 is a front elevation view thereof;
FIG. 6 is a top plan view thereof;
FIG. 7 is a bottom plan view thereof; and
FIG. 8 is a bottom perspective view thereof.
FIG. 9 is a top perspective view of a blade for oscillating power tools showing our new design in accordance to a second embodiment;
FIG. 10 is a right side elevation view thereof;
FIG. 11 is a left side elevation view thereof;
FIG. 12 is a rear elevation view thereof;
FIG. 13 is a front elevation view thereof;
FIG. 14 is a top plan view thereof;
FIG. 15 is a bottom plan view thereof; and
FIG. 16 is a bottom perspective view thereof.
FIG. 17 is a top perspective view of a blade for oscillating power tools showing our new design in accordance to a third embodiment;
FIG. 18 is a right side elevation view thereof;
FIG. 19 is a left side elevation view thereof;
FIG. 20 is a rear elevation view thereof;
FIG. 21 is a front elevation view thereof;
FIG. 22 is a top plan view thereof;
FIG. 23 is a bottom plan view thereof; and
FIG. 24 is a bottom perspective view thereof.
FIG. 25 is a top perspective view of a blade for oscillating power tools showing our new design in accordance to a fourth embodiment;
FIG. 26 is a right side elevation view thereof;
FIG. 27 is a left side elevation view thereof;
FIG. 28 is a rear elevation view thereof;
FIG. 29 is a front elevation view thereof;
FIG. 30 is a top plan view thereof;
FIG. 31 is a bottom plan view thereof; and
FIG. 32 is a bottom perspective view thereof.
FIG. 33 is a top perspective view of a blade for oscillating power tools showing our new design in accordance to a fifth embodiment;
FIG. 34 is a right side elevation view thereof;
FIG. 35 is a left side elevation view thereof;
FIG. 36 is a rear elevation view thereof;
FIG. 37 is a front elevation view thereof;
FIG. 38 is a top plan view thereof;
FIG. 39 is a bottom plan view thereof; and
FIG. 40 is a bottom perspective view thereof.
FIG. 41 is a top perspective view of a blade for oscillating power tools showing our new design in accordance to a sixth embodiment;
FIG. 42 is a right side elevation view thereof;
FIG. 43 is a left side elevation view thereof;
FIG. 44 is a rear elevation view thereof;
FIG. 45 is a front elevation view thereof;
FIG. 46 is a top plan view thereof;
FIG. 47 is a bottom plan view thereof; and
FIG. 48 is a bottom perspective view thereof.
FIG. 49 is a top perspective view of a blade for oscillating power tools showing our new design in accordance to a seventh embodiment;
FIG. 50 is a right side elevation view thereof;
FIG. 51 is a left side elevation view thereof;
FIG. 52 is a rear elevation view thereof;
FIG. 53 is a front elevation view thereof;
FIG. 54 is a top plan view thereof;

FIG. 55 is a bottom plan view thereof; and
FIG. 56 is a bottom perspective view thereof.
FIG. 57 is a top perspective view of a blade for oscillating
power tools showing our new design in accordance to an
eighth embodiment;
FIG. 58 is a right side elevation view thereof;
FIG. 59 is a left side elevation view thereof;
FIG. 60 is a rear elevation view thereof;
FIG. 61 is a front elevation view thereof;
FIG. 62 is a top plan view thereof;
FIG. 63 is a bottom plan view thereof; and,
FIG. 64 is a bottom perspective view thereof.
The broken lines in the drawings illustrate portions of the
blade for oscillating power tools that form no part of the
claimed design.
